FINGER RING

Moe Manne, Hewlett, N. Y.

Application May 26, 1953, Serial No. 25,192

Term of patent 3½ years

(Cl. D45—10)

To all whom it may concern:

Be it known that I, Moe Manne, a citizen of the United States, resident of the city of Hewlett, in the county of Nassau, State of New York, have invented a new, original, and ornamental Design for a Finger Ring, of which the following is a specification, reference being had to the accompanying drawing, forming part hereof.

In the drawing:

Fig. 1 is a top plan view of a finger ring, showing my new design;

Fig. 2 is a front elevational view thereof; and

Fig. 3 is a side elevational view thereof.

The dominant features of my design reside in those portions shown in full lines.

I claim:

The ornamental design for a finger ring, substantially as shown and described.

MOE MANNE.
